UNITED STATES PATENT OFFICE.

DAVID A. DECROW, OF BUFFALO, NEW YORK, ASSIGNOR TO WORTHINGTON PUMP AND MACHINERY CORPORATION, A CORPORATION OF VIRGINIA.

STEAM PUMPING-ENGINE.

1,380,365.

Specification of Letters Patent. Patented June 7, 1921.

Application filed April 3, 1918. Serial No. 226,509.

To all whom it may concern:

Be it known that I, DAVID A. DECROW, a citizen of the United States, residing at Buffalo, county of Erie, and State of New York, have invented certain new and useful Improvements in Steam Pumping-Engines, fully described and represented in the following specification and the accompanying drawings, forming a part of the same.

10 This invention relates to steam engines and particularly to a combined engine and pump, the especial object of the invention being to provide a steam operated pumping engine capable of operating efficiently and 15 economically at very high speeds.

A further object of the invention is to provide a steam engine particularly adapted for high speed pumping that is simple and convenient in its construction and includes valve gear that is readily assembled and taken down.

The following specification describes and the accompanying drawings illustrate an engine constructed in accordance with the 25 invention, it being understood that changes may be made in the form, construction and arrangement of the parts without departing from the invention, the form herein disclosed being a preferred embodiment thereof.

30 In the drawings:—

Figure 1 is a view in side elevation of a combined engine and pump constructed in accordance with the invention.

Fig. 2 is a top plan view of a portion of 35 the same.

Fig. 3 is an enlarged cross sectional view, with parts in plan.

Fig. 4 is an enlarged cross sectional view 40 showing a portion of Fig. 3 in a different section, and

Fig. 5 is a vertical sectional view with parts in elevation.

Referring to the drawings, the engine is a double acting uniflow engine having the 45 piston 21 and cylinder 22. Steam is admitted as hereinafter described alternately at each end of the cylinder through steam chests 37 having supply pipes 38, 39, and exhausts through central ports 23 into exhaust belt 24. Piston 21 is mounted on a piston rod 25 having suitable connection with the engine crank (not shown) which drives the engine shaft 26 and 27 is the plunger rod of the pump. The pump is tied to the engine by rods 28 and is shown as a double

acting center packed pump, having pulsation chambers 29, suction chamber 30, suction pipe 31, discharge and air chambers 32 and discharge pipes 33, with common delivery pipe 34.

The invention includes a construction such that the valve gear for controlling the admission of steam to the cylinder is readily removable entirely and is also readily taken down for removal of various parts. 60 To this end, the valve gear at each end of the cylinder is so located that the axial line thereof is offset from the plunger rod 27 or piston rod 25 so that the valve stem may be withdrawn past these and bodily removed. 70 The valve chests and valve gear at opposite ends of the cylinder are the same, so that description of one will suffice. Referring more particularly to Figs. 3 and 5, the cylinder is connected with the valve chest by 75 a port 43 controlled by the valve 44. This valve is detachably mounted on a valve stem 45. To this end the valve has a central hub portion 46 which bears against a collar 47 on the stem 45 and is held in place by a nut 48. The valve chest 37 has a cap 49, the removal of which gives access to the valve. By removing the nut 48, the valve may be detached from the stem and drawn out from the valve chest.

The valve stem slides in a tubular guide member 50 detachably supported by a housing 51. The guide member 50 has an annular shoulder 52 which seats on the rim of a sleeve 53 carried by the housing 51 and 80 below the sleeve 53 the guide member is threaded to receive a nut 54 which detachably secures it in place. The valve gear is operated by a cam 55 hereinafter referred to, and to this end the valve gear includes 85 a head 56 sliding in the housing 51 and carrying a pin 57 on which is mounted a cam roller 58. The roller is kept to its duty by a spring 59 bearing, respectively, against the head 56 and an abutment plate 60 removably secured to the housing 51. The valve stem is detachably connected to the head 56. As shown, the end of the stem is threaded into the head and is held in place by a lock nut 61. The housing 51 is provided with caps 105 62 which may be removed to give access to the nuts 54 and 61 and the plate 60. If the nut 61 is removed, valve and valve stem may be withdrawn. By removal of nut 54 and the abutment plate 60 the entire valve 110

gear down to the head 56 is bodily removable, and the head 56 and spring 59 may be withdrawn through the opening covered by cap 62 by removing pin 57 or may be withdrawn downward with the pin and roller by removing cam 55 and its shaft.

The valve construction above described is not only extremely simple and convenient, but at the same time all the moving parts of the valve gear are inclosed by the valve chest or housing.

The cams 55, which actuate the valve gear have a differential circumference, and are designed to give the valves a varying point 15 of cut off depending on their longitudinal position with respect to their rollers. These cams, which are duplicates, are rotated by a cam shaft 64 driven by a worm gear indicated at 65, operated as usual from the engine shaft.

The invention includes provision for the regulation of the speed of the engine dependent on both the engine speed and the pressure of the fluid being pumped. This 25 is accomplished by causing longitudinal movement of the cam shaft to vary the point of cut off. In the present embodiment, the cam shaft 64 is made in two parts coupled together by a sleeve 63 fixed to the driving 30 part of the cam shaft and in which sleeve the part of the cam shaft carrying the cam is splined so as to be capable of longitudinal movement while rotating with the sleeve and driving part of the shaft. Mounted on the 35 cam shaft is a centrifugal ball governor 67 having one end of its links pivoted to a sleeve 10 splined on the shaft and free to move longitudinally thereon, and the other end pivoted to a sleeve 11 which is splined 40 on the shaft to rotate therewith but fixed against longitudinal movement. This governor moves the cam carrying portion of the cam shaft 64 to the right in the figures as the governor weights are thrown out, by engagement of sleeve 10 with collar 12 fixed 45 on the shaft, and permits the return of the shaft by spring 80 on the movement of the sleeve 10 to the left as the weights move inward, thereby moving the cams to vary the 50 point of cut-off, this variation depending upon the engine speed.

The cam shaft 64 is shifted also in accordance with the pump pressure, the speed of the pump thus being regulated by the 55 pump pressure independently of the centrifugal speed governor.

Connected to the end of the shaft 64 (Figs. 3 and 4) is a sleeve 69 having a piston fit in a cylinder 70 which is secured to the 60 housing 51. As shown, the sleeve carries a collar 71 engaged by a bearing 72 on the shaft and secured by nut 73. Sleeve 69 is formed with a shoulder as appears at 74, and behind this shoulder an annular channel 65 75 is formed in the cylinder 70. A fluid

under pressure is admitted into this channel so as to subject the sleeve to a pressure depending on the pump pressure. To this end, opening into channel 75 is a pipe 76 leading to a pressure regulator 77 connected in turn by a pipe 78 with the delivery pipe or air chamber of the pump. This pressure regulator contains a fluid, the pressure of which is dependent on the pump pressure. The regulator pressure being transmitted 75 to channel 75, its force is exerted against the shoulder 74 of the sleeve thereby tending to move the sleeve longitudinally to the right in the figures. This movement shifts the cam shaft and the cams. An opposing pressure is derived from a coil spring 80 bearing against a head 81 formed on the sleeve, and against a collar 82. For adjustment of the spring pressure, the collar is threaded onto a sleeve 83 which is rotated by a hand wheel 84. To prevent collar 82 from rotating with sleeve 83, the collar carries a pin 85 moving in a slot in cylinder 70. Sleeve 69 preferably carries a pointer 88 moving over a scale to show the point of cut-off. For manual adjustment of the cam shaft and cams, a hand wheel 86 is threaded onto a stem 87 secured to head 81 of the sleeve 69. This pressure regulator for controlling the cut off by the pump pressure is preferably used, but it will be understood that the construction may be used without it, in which case the port 75 will connect only with the dash pot 98 with adjustable needle valve 99 which is preferably used in all cases to check vibration. 100

It will be seen that the combined centrifugal governor and pressure governor operates as follows:

The pumping pressure controls the point of cut off by acting on the piston or shoulder 74 for earlier cut off as the pressure rises, spring 80 acting to return the piston and cam shaft 64 for later cut-off as the pressure falls, this action being independent of the centrifugal governor, the cam shaft 64 and collar 12 moving freely through the sleeves 10, 11. The pressure will thus control the speed so as to maintain under normal conditions a substantially uniform pressure and speed independently of the centrifugal governor. If the speed rises too high, the centrifugal governor weights will fly out sufficiently so that the sleeve 10 engages the collar 12 and moves the cam shaft 64 to the right independently of the pressure governor to advance the cut-off and reduce the speed, this centrifugal governor thus acting as a safety device to assure the proper speed control. If the pressure governor be not used, as described above, the control of the 120 cut-off will be wholly by the centrifugal governor acting to move the cam shaft 64 against spring 80 and to control the return of the cam shaft by the spring. 125

Means is provided for stopping the engine 130

when the cam shaft has been shifted to a determined point. This is done by locking the shaft against any relative movement, thereby cutting off the steam supply. In the 5 present embodiment, in the wall of cylinder 70 is a spring pressed latch 90 having a slanting face toward the sleeve 69. In this sleeve, near the end, is an annular groove 91. Latch and groove are so positioned that 10 when the cam shaft has been shifted by the centrifugal governor or pressure governor to such an extent that the cams are no longer operating the valve gear, the latch slides into the groove and the sleeve is locked to prevent 15 return of the cam shaft. As a result, the steam supply is shut off from the engine until the latch 90 is manually released.

As shown, means are provided for breaking the condenser vacuum through pipe 92 20 leading to the condenser. Connected therewith is an air pipe 93 normally closed by a valve designated at 94. This valve is operated by a rod 95 having a collar 96 against which bears a trigger 97. The end of this 25 trigger is located in the path of the sleeve 69. When sleeve 69 has reached a given position, its end strikes the trigger 97 and thus opens the valve 94 and admits air to the condenser.

30 The operation of the combined engine and pump will be clear from the foregoing without further description.

What is claimed:

1. In a combined engine and pump, a 35 valve gear for controlling the steam supply of the engine, a centrifugal speed governor and valve control mechanism for varying the point of cut off, a connection between the centrifugal speed governor and valve control mechanism permitting the valve control mechanism to move independently of the speed governor, and a pressure governor controlled by the pressure of the fluid being pumped, connected to the valve control 40 mechanism to vary the point of cut off independently of the speed governor, and operable without lost motion regardless of the position of the valve control mechanism under movement by the speed governor. 45

50 2. In a combined engine and pump, a cam shaft rotated by the engine, a cam mounted on said shaft for operating the engine valve gear, and means for adjusting said cam to regulate the speed of the engine in accordance with the speed of said shaft and for adjusting said cam by the pressure of the fluid being pumped and independently of the speed.

55 3. In a combined engine and pump, valve gear for controlling the steam supply of the engine, a cam shaft rotated by the engine and capable of longitudinal movement, a differential cam, mounted on said shaft, for operating said valve gear, and means for longitudinally moving said cam shaft in ac-

cordance with the speed of the engine and independently of the speed in accordance with the pressure of the fluid being pumped.

4. In a combined engine and pump, valve gear for controlling the steam supply of the engine, a cam shaft rotated by the engine and capable of longitudinal movement, a differential cam mounted on said shaft for operating said valve gear, a centrifugal governor associated with said shaft to longitudinally move the same in accordance with its speed, and pressure operated means dependent on the pressure of the fluid being pumped for longitudinally moving said shaft independently of the centrifugal governor. 75

5. In a combined engine and pump, valve gear for controlling the steam supply of the engine, a cam shaft rotated by the engine and capable of longitudinal movement, a differential cam mounted on said shaft for operating said valve gear, a centrifugal governor for longitudinally moving said cam shaft in accordance with the speed, and means for longitudinally moving said cam 90 shaft in accordance with the pressure of the fluid being pumped independently of the centrifugal governor. 95

6. In a combined engine and pump, valve gear for controlling the steam supply of the engine, a cam shaft rotated by the engine and capable of longitudinal movement, a differential cam mounted on said shaft for operating said valve gear, a centrifugal governor on said shaft mounted to permit 100 the shaft to move longitudinally independently of the centrifugal governor, a cylinder, a sleeve therein connected with said cam shaft for longitudinal movement therewith, said sleeve having a pressure receiving 105 portion, means for subjecting said sleeve to pressure dependent on the pressure of the fluid being pumped, and a spring for pressing said sleeve in the opposite direction. 110

7. In a combined engine and pump, valve gear for controlling the steam supply of the engine, a cam shaft rotated by the engine and capable of longitudinal movement, a differential cam mounted on said shaft 115 for operating said valve gear, means for longitudinally moving said cam shaft in accordance with the pressure of the fluid being pumped, and means for locking said shaft to stop the engine when it has reached 120 a determined position.

8. In a combined engine and pump, valve gear for controlling the steam supply of the engine, a cam shaft rotated by the engine and capable of longitudinal movement, a 125 differential cam mounted on said shaft for operating said valve gear, a centrifugal governor associated with said shaft to longitudinally move the same in accordance with its speed, and means for locking said shaft 130

to stop the engine when it has reached a determined position.

9. In a combined engine and pump, valve gear for controlling the steam supply of the engine, a cam shaft rotated by the engine and capable of longitudinal movement, a differential cam mounted on said shaft for operating said valve gear, a centrifugal governor associated with said shaft to longitudinally move the same in one direction in accordance with its speed, a spring for returning the shaft, a pressure governor controlled by the pressure of the fluid being pumped and connected for longitudinally moving said shaft independently of the centrifugal speed governor, and a fluid dash-pot for checking the movements of the shaft.

10. In a combined engine and pump, valve gear for controlling the steam supply of the engine, a cam shaft rotated by the engine and capable of longitudinal move-

ment, a differential cam mounted on said shaft for operating said valve gear, a centrifugal governor on said shaft having its 25 shaft-moving member free to slide on the shaft and engaging a fixed member on the shaft for moving the latter, whereby the shaft may be moved longitudinally for earlier cut-off independently of the centrifugal 30 governor or by the centrifugal governor on engagement with said fixed member on the shaft, means for longitudinally moving said cam shaft independently of the movement of the centrifugal governor and in accordance with the pressure of the fluid being pumped, and a spring for returning the cam shaft, whereby the steam supply is controlled independently by the centrifugal 35 governor and the pressure governor. 40

In testimony whereof, I have hereunto set my hand.

DAVID A. DECROW.
